UNITED STATES PATENT OFFICE.

CHARLES W. AGERELL, OF CHICAGO, ILLINOIS.

GAS-ENGINE.

1,231,550.

Specification of Letters Patent.

Patented July 3, 1917.

Application filed May 6, 1912, Serial No. 695,441. Renewed November 20, 1916. Serial No. 132,494.

To all whom it may concern:

Be it known that I, CHARLES W. AGERELL, a citizen of the United States, residing at Chicago, in the county of Cook and State 5 of Illinois, have invented a certain new and useful Improvement in Gas-Engines, of which the following is a specification.

My invention relates to improvements in gas engines and is illustrated diagrammatically in one form in the accompanying drawings, wherein—

Fig. 1 is a side elevation with parts broken away and parts in section;

Fig. 2, a section along the line 2—2 of 15 Fig. 1;

Fig. 3, a detail plan view of the valve seat;

Fig. 4, a detail plan view showing the valve resting upon the valve seat in the same position as that shown in Figs. 1 and 20 2 with the inlet open;

Fig. 5 is a similar view showing all the ports closed;

Fig. 6, a similar view showing the exhaust open;

Fig. 7 is a plan view of the valve disk;

Fig. 8, a detail side elevation of the modified form.

Like parts are indicated by like letters in all the figures.

The engine base A, which carries at its top the water-jacketed engine cylinder A¹, supports the bearings A² A³ in which is rotatably mounted the crank shaft A⁴ having the crank A⁵. The piston A⁶ reciprocates in the cylinder A¹ and is connected by means of the rod A⁷ to the crank shaft A⁴.

The pinion B is rigidly mounted on the crank shaft A⁴ in mesh with the gear B¹ 40 rotatably mounted on the frame A. The front face of the gear B¹ contains the cam slot B² in which is rotatably and slidably mounted the cam roller B³ carried on the pin B⁴. The link B⁵ is freely pivoted at one end on the pin B⁴ and at the other end on the lug B⁶ in the engine frame A.

The valve pocket C is located at one side of the cylinder adjacent its top and contains the rotatable valve disk C¹ rigidly mounted 50 on the shaft C². The crank C³ is mounted on the shaft C² and carries pivotally mounted thereon the link C⁴ which is pivotally mounted at the other end on the cam pin B⁴. The valve disk C¹ is in slidable and 55 rotatable contact with the valve seat plate C⁵ which forms one wall of the valve cham-

ber C and which has the four radially arranged ports C⁶ C⁷ C⁸ and C⁹ therein. The ports C⁶ C⁷ lead to the exhaust chamber D from which discharges the exhaust pipe D¹ 60 and the ports C⁸ C⁹ lead to the intake chamber D² which is supplied by the intake pipe D³.

The valve disk C¹ is provided with the two ports E E¹ and the single larger port E². The ports C⁶ C⁷ C⁸ C⁹ in the valve seat are separated each by an angle of 90° and the ports E E¹ and E² are so arranged that when one side of the port E² is in register with the port C⁸ the port E¹ will 70 be in register with the port C⁹ and when the port E² is located intermediate the ports C⁷ C⁸ the ports E E¹ will be out of register with any of the ports in the valve seat and when the port E² is in register on its opposed side with the port C⁷ the port E will 75 be in register with the port C⁶. By this arrangement as the valve disk oscillates the port E² is at one time in register with the exhaust port and at another time in register with the intake port, and the port E is at one time in register with the exhaust port and at another time closed and the port E¹ is at one time in register with the intake port and at another time closed. In other 80 words, the port E acts always as an exhaust port, the port E¹ always as an intake port and the port E² alternately as an exhaust and intake port.

The housing F contains the exhaust and 90 intake chambers D D² and carries on its upper side the grease cup F¹ which discharges through the passage F² to the bearing surface C⁶ to a point beneath the valve disk C¹. At this point the passage communicates with the grooves F³ F⁴ which 95 communicate, as indicated, with the oiling groove system surrounding the intake and exhaust ports.

In the modified form indicated in Fig. 8 100 the valve disk, valve seat and intake and exhaust chambers are located at the head of the cylinder instead of on one side and, therefore, a cylindrical combustion chamber is provided. When this arrangement is 105 used the link G is substituted for the link C⁴ and it is pivotally mounted to the bell crank lever G¹ pivoted on the cylinder head G². This bell crank lever carries at the other end the ball and socket joint G³ which 110 carries the link G⁴ pivoted on the arm G⁵ to rock the shaft G⁶ to operate the valve.

The spring H surrounds the shaft C² and shaft G⁶ and presses at one side on the sleeve H¹ and at the other side on the casting F or the cylinder head G² as the case 5 may be, to yieldingly hold the valve disk against the valve seat and thus cause the valve to seat snugly but at the same time prevent any binding or scarring such as might be caused by the differential expansion and contraction caused by change in 10 temperature.

It will be evident that, while I have shown in my drawings an operative device, still many changes might be made in size, shape 15 and arrangement of parts without departing materially from the spirit of my invention, and I wish therefore that my drawings be regarded as in a sense diagrammatic.

The use and operation of my invention are 20 as follows:—

As the engine turns over the crank shaft rotates and the large gear makes but one revolution to two of the crank shaft. By virtue of the fact that the cam roller is in 25 engagement with the cam slot the vertical link is reciprocated, the horizontal link oscillating to hold the cam roller in the correct position.

The shape of the cam slot is such that the 30 timing of the valve is as follows: Supposing the piston to be going up on the exhaust stroke the valve disk will be rotated so that two of the ports will be in register with the two exhaust ports. The cam is designed so 35 that there will be no movement of the valve disk until just as the end of the stroke is reached. At this instant the cam will cause the link to move and oscillate the valve disk so as to bring two of the ports in the valve 40 disk into register with the two intake ports. This condition continues until the end of the downward suction stroke. Just as the piston reaches the end of the suction stroke the cam causes the valve disk to rotate to close the 45 ports and the compression stroke takes place without any further rotation of the valve disk. The firing stroke also takes place without any further rotation of the valve disk and, just as the end of the firing stroke is 50 reached when the pressure in the cylinder is a minimum, the disk opens the exhaust port. This cycle will continue indefinitely. It will be noted that the cam slot is carefully 55 designed so that every motion of the valve disk will take place only at times when the pressure is least in the valve chamber and this valve disk movement will be very rapid and alternated with long periods of rest. By this arrangement there is very slight 60 danger of scarring or binding the valve disk. But small power would be required to rotate

or oscillate the valve disk because the movement takes place when there is very little pressure tending to force the disk upon its seat and the firing and compression stroke 65 will take place with the valve practically at rest at all times, thus preventing to a very large extent the possibility of carbonizing, pitting and the like which would result in loss of compression or loss of power. 70

I claim:

1. In a combustion engine a flat valve seat, two intake and two exhaust ports in said seat and a perforate valve disk controlling them, and means for oscillating said disk to intermittently bring the perforations in said disk into register with the ports. 75

2. In a combustion engine a flat valve seat, two intake and two exhaust ports in said seat and a valve disk controlling them, said valve disk being located in the combustion chamber, and means for oscillating said disk to intermittently bring the perforations in said disk into register with the ports. 80

3. In a combustion engine a valve comprising a flat perforate disk, the perforations therein being three in number, one of them being twice the size of either of the other two. 85

4. In a combustion engine a valve comprising a flat perforate disk, the perforations therein being three in number, one of them being twice the size of either of the other two, the center line of the larger port being spaced 90° from the nearest side of either of the other ports. 90

5. In a combustion engine a flat perforate valve disk, one of said perforations serving alternately as an intake and an exhaust port, one of the others serving only as an intake 100 and one only as an exhaust port.

6. In a combustion engine a flat valve seat, two intake and two exhaust ports therein, said ports being separated by angles of 90°, a perforate valve disk controlling said ports 105 and means for oscillating said disk to open and close both intake and exhaust ports in response to the movement of the engine.

7. In a combustion engine a flat valve seat, intake and exhaust ports in said seat arranged 90° each from that adjacent to it, said ports being bounded on their inner and outer sides by concentric curved lines and on their other sides by radii and an oscillating valve disk on the side oscillating about 110 the center of said circle to control said ports. 115

Signed at Chicago, Illinois, this 2nd day of May 1912.

CHARLES W. AGERELL.
